HORN HOUSING

Charles E. Graham Reeves, Summit, N.J., assignor to
Falcon Alarm Co., Inc., Summit, N.J., a corporation
of New Jersey

Application November 18, 1957, Serial No. 48,499

Term of patent 14 years

(Cl. D72—1)

Fig. 1 is a side elevational view of a horn housing showing my new design;

Fig. 2 is an elevational front view of the horn housing shown in Fig. 1; and

Fig. 3 is an elevational rear view of the horn housing shown in Fig. 1.

The essential features of my design reside in the portions shown in full lines, with the broken lines showing of the horn bell omitted from Figs. 2 and 3 for convenience of illustration.

I claim:

The ornamental design of a horn housing, substantially as shown and described.
